To all whom it may concern:

Be it known that I, Marian Worthington Keith, a citizen of the United States, residing at Washington, District of Columbia, have invented a new, original, and ornamental Design for a Jacket, of which the following is a specification, reference being had to the accompanying drawing, forming a part thereof.

Fig. 1 is a front view of a jacket showing my new design; and,

The jacket is designed as an article of women's apparel.

The characterizing feature of the jacket is a double-breasted front wherein the exposed panel extends well beyond the medial front line and is defined by a side edge which meets the low point of a V-shaped neck portion in the vicinity of the shoulder.

I claim:

The ornamental design for a jacket, as shown and described.
